UNITED STATES PATENT OFFICE.

WILLIAM FREMONT GLIDDEN, OF INGERSOLL, CANADA.

BICYCLE-WHEEL BELT.

SPECIFICATION forming part of Letters Patent No. 605,181, dated June 7, 1898.

Application filed January 23, 1896. Serial No. 576,618. (No model.)

To all whom it may concern:

Be it known that I, WILLIAM FREMONT GLIDDEN, a citizen of the United States, and at present a resident of Ingersoll, in the county of Oxford, in the Province of Ontario, Canada, have invented a new and useful Bicycle-Wheel Belt and Tension Device Therefor, of which the following specification, taken in connection with the accompanying drawings, forms a full, clear, and exact description.

This invention relates to a belt and tension device therefor which is particularly adapted to be used in connection with bicycles and the like, but it may be used with advantage in any place or position or in any machine where a similar belt is required; and it consists of a belt composed of a flexible protecting-strap, band, or shield, of flexible extensions, one end of which is secured to or formed integral with the edge of said shield, a series of said extensions extending laterally from both edges of said shield and provided with loops or eyes at their outer ends, and cords, one of which extends through the loops or eyes of each series of said flexible extensions at each side of the shield, and it also consists of the improved construction and combination therewith of means for regulating the tension of said belt on the tire of the bicycle-wheel or other device in connection with which it may be used, the object contemplated being the provision of a simple and efficient device for avoiding and completely preventing the tires of bicycle-wheels from being punctured or otherwise injured.

In order that my invention may be readily understood, I have illustrated the same in the accompanying drawings in connection with a bicycle.

In the drawings, Figure 1 is a view of a bicycle, showing the application of my invention. Fig. 2 is an enlarged detail plan view of a short portion of my improved belt before being placed in position. Fig. 3 is a cross-sectional view on the line $x' x'$ of Fig. 2. Fig. 4 is an enlarged detail perspective view of a short portion of my improved belt, showing its form after being placed in position. Fig. 5 is a cross-sectional view on the line $y y$ of Fig. 4. Figs. 6 and 7 are enlarged detail perspective views of the mechanism

for regulating the tension on the front and rear wheels, respectively. Fig. 8 is a detail perspective view of the braces and connections. Fig. 9 is an enlarged detail perspective view of the semicylindrical bearing. Fig. 10 is an enlarged detail front end view of the pulley-frame, showing the spring and adjacent attachments and a portion of the bicycle-tire. Fig. 11 is an enlarged detail end view of the braces, showing the standards and shaft connected therewith.

In the accompanying drawings, A designates a protecting strap, band, or shield, preferably formed of rawhide; but it may be formed of any other suitable flexible material.

B B designate flexible extensions formed of rawhide, catgut, or other suitable material, one end of which flexible extensions B is secured to or formed integral with the edge of the shield A, and a series of these flexible extensions B extend laterally from both edges of said shield, as shown in Fig. 2 of the accompanying drawings, and secured to or formed integral with the outer end of these extensions B are the loops or eyes B'.

C C designate cords formed of rawhide, catgut, or other suitable material, one of which cords C extends through the loops or eyes B' of each of the series of flexible extensions B B at each side of the shield A, also shown in Fig. 2 of the accompanying drawings.

E E designate standards, the lower ends of which are rigidly secured to the fork sides D D of the bicycle by the clasps d'.

I I designate braces, which are also rigidly secured to the fork sides D D by the clasps d'. The other ends of these standards E E and braces I I are hung on the shaft G and are rigidly held in place thereon between the nuts n' n'.

F designates a bearing formed with the curved face f' and with the end flanges or shoulders f', and this bearing F is pivoted eccentrically on the shaft G.

K designates a plate of spring-steel or other suitable material provided with the flanges or shoulders K', one end of which spring K is rigidly secured to the braces I, and this spring K rests on the curved face f' of the bearing F, as shown in Fig. 6.

L designates an antifriction wheel or pul-

ley which rotates freely on the axle M, and the latter is supported in the frame N, and said frame N is secured to and near the outer end of the spring K and adjacent to the bicycle-tire by the thumb-nut b', engaging with the screw-threaded shank a', the latter being secured to or formed integral with the frame N. The shank a' projects through a corresponding opening in the spring K, and the latter is clamped to the frame N by the nut b', and the flanges K² are formed on the spring K to come opposite to the frame N to hold the latter in place and to prevent it from accidentally turning on the shank a', and this frame N is provided with two or more bearing-notches N³ to permit wheels of different diameter to be used in said frame.

b² designates an operating-rod provided with the teeth a², one end of which rod is pivotally secured to the bearing F, and c' designates a standard provided with the slot or opening c², through which the rod b² projects. This standard c' is provided with a screw-threaded shank c³, which extends through corresponding openings in the spring K and the braces I, where the latter cross one another, and is held in place by a nut n³, screwing on the screw-threaded shank c³, and when the nut n³ on the lower end of the standard c' is tightened the spring K is rigidly secured to the braces I between the shoulder e' on the standard c' and the braces I by said nut n³. This will form one convenient means for rigidly holding the fixed end of the spring K.

K' designates a spring similar to the spring K, the fixed end of which spring K is rigidly secured by the clamp d³ to the inclined tube O of the bicycle-frame.

L' designates an antifriction wheel or pulley, N' a frame, and M' an axle attached to the spring K' the same as the similar devices are secured to the spring K.

F² designates a bearing constructed similarly to the bearing F, which bearing F² is pivotally supported eccentrically on a shaft G', having bearings in the hangers P, the latter being rigidly clamped or otherwise secured to the inclined tube O' of the frame.

b³ designates an operating-rod provided with teeth a³ similar to the rod b², and said operating-rod b³ is secured to the bearing F² and in the same manner as the rod b² is secured to the bearing F, and said rod b³ extends through slots or openings b⁶ in flanges b⁴ and b⁵ of the clamps d⁴ and d⁵, the latter being secured to the tube O' of the bicycle-frame, and these rods b² and b³ are held, as well as the bearings F and F² and springs K and K', respectively connected therewith at the position to which they may be adjusted by engaging the teeth a² and a³, respectively, with one of the edges of the standard c' and flange b⁴, respectively, around the openings therein, the tension of the springs K and K' on the rods b² and b³ holding said teeth a² and a³, respectively, in contact with the flange b⁴ and

standard c', respectively, to avoid and prevent their accidental disengagement.

When properly adjusted on the bicycle, the springs K and K' rest on the bearings F and F², respectively, and said springs are securely held in proper position from moving laterally independent of said bearings by the shoulders or projections f'.

When adjusted as described, the antifriction wheels or pulleys M and M' are held in line with the front and rear bicycle-wheels R and R', respectively.

Before placing the shield A in position to protect the tire from being punctured or otherwise injured the teeth a² and a³ of the operating-rods b² and b³, respectively, are disengaged from the edges of the standard c' and flange b⁴, surrounding the openings therein, to permit the antifriction wheels or pulleys L and L' to be adjusted as near as possible adjacent to the tire. The cords C C are then inserted in and extended through the loops B' of the flexible connections B, as shown in Fig. 2. The belt thus formed is then placed on the tire around the wheel and over the antifriction-pulley and the ends of the shield united by suitable means. The operating-rod and bearing are then adjusted, and the latter eccentrically to act on the spring K and pulley L to cause the latter to take up any slack in the shield A, after which the cords C C are drawn taut. This curves the shield A over the outer face of the tire until the cords C are about parallel with the metallic rim of the wheel, and these cords are held in this position by a hook secured to one end engaging with holes in the other end of said cord or in any manner or by any means found most suitable or convenient. This causes the shield A to cover and rest on the tread of the tire in order to protect the latter.

After the belts for both wheels have been placed in position, as described, by adjusting the operating-rods b² and b³ the bearings F and F², respectively, are adjusted to act eccentrically on the springs K and K', respectively, to adjust the outer end of the springs K and K' and pulleys L and L' from the bicycle-wheels R and R' to give the required tension to the belts passing over said pulleys L and L', and the handles of these operating-rods b² and b³ are adjusted within convenient reach of the rider, so that they may be readily and easily operated to regulate the tension of the belt while the bicycle is in motion.

The open space or width between the arms x x of the frame N, in which the spindle M is supported, is greater than the thickness of the pulley L, so that the latter may be adjusted automatically and laterally on said spindle M by the belt to permit the pulley L to automatically keep in line with the wheel if the latter should not be hung perfectly true, and, as shown in Fig. 10 of the accompanying drawings, the antifriction wheels or pulleys L have a wider periphery than the

bicycle-tire, so that as the belt leaves the tire and passes over the pulley L and onto the tire again said cords C will be slightly spread by said pulley L, and thereby be prevented from chafing or injuring the tire in any way when passing from the tire and over the pulley L and onto the tire again.

By constructing the belt as described the shield A fits on the tread of the tire and the cords C being connected to the shield A by the flexible extensions B, but being permitted to move lengthwise through the loops B' independent of the shield, the belt fits snugly on the tire without being puckered at the edges, whereas if the belt was made in one continuous web or piece it would pucker when placed in position and appear unseemly, as well as gather sand, &c., while the bicycle was traveling along the road, whereas the edges of my improved belt being open all of which is avoided and completely prevented, and a belt formed as described automatically adapts itself to tires of different diameter or diameters, as well as to tires of different diameter or width in cross-section, and to assist in accomplishing this result the pulley or roller L is made interchangeable, so that another roller of larger or smaller diameter and formed with a wider or narrower periphery or outer face may be used to facilitate the adjustment of one belt to the tires of bicycle-wheels of different diameter.

While I prefer the construction herein shown and described, I do not wish to confine or limit myself to the details thereof, as they may be modified in various ways without departing from the spirit of my invention; nor do I wish to confine myself to the use of this invention in connection with a bicycle, as there are various other machines to which it may be applied with equal advantage.

Having thus described my invention, I claim—

1. In a bicycle-wheel belt, a flexible shield which fits snugly over the tire of the wheel, and two series of straps secured to the shield, and extending laterally thereto, combined with cords which connect the outer ends of the extensions at a suitable distance from the edge of the shield, substantially as shown.

2. A belt composed of the shield, A, straps, B, provided with the loops or eyes, B', and the cords, C, in combination with and extending around a wheel-tire and over an antifriction roller or pulley, and means for supporting the latter, the periphery or outer face of the antifriction roller or pulley being wider than the periphery or outer face of the wheel-tire for the purpose of spreading the belt as it passes from and on to the wheel-tire to prevent the latter from being rubbed or injured, substantially as set forth.

3. In a bicycle, a belt, the front wheel around which the belt extends, and an antifriction-roller arranged over the wheel, and over which roller the belt passes, combined with a supporting-spring for the roller, and

which spring extends over the top of the wheel; an eccentrically-pivoted bearing which supports the spring at a point in between its two ends, and by which the tension of the roller upon the belt is regulated; and means connected to the inner end of the spring for securing it in position, substantially as shewn.

4. A belt consisting of a shield, A, straps, B, provided with the loops or eyes, B', and cords, C, extending around the tread of the wheel-tire and over the antifriction roller or pulley, in combination with a spring, and an eccentrically-pivoted bearing and means for supporting and operating the latter, substantially as and for the purpose set forth.

5. In a bicycle, the front forks D, D, the standards E, E, secured thereto at their lower ends and projecting upwardly, and the braces I, I, connected both to the forks at one end, and to the standards at the other, combined with a shaft G which passes through both the braces and the forks, a spring, means for securing it to the bicycle-frame, a roller supported by its front end, a belt, the front wheel of the bicycle around which and pulley, the belt passes; an eccentric bearing placed upon the shaft, a suitable support for the front of the eccentric bearing, and a support for the forks I, which is attached at its upper end to the support for the bearing, substantially as shown.

6. The front forks D, D, the standards E, E, secured thereto at their lower ends, the braces I, I, secured to the forks at their rear ends, and to the upper ends of the braces at their front ones, the rod G which connects the front ends of the braces and the front ends of the standards, combined with an eccentric bearing that is pivoted upon the rod at its rear end, a support for the front edge of the bearing, a support which is secured to the forks at its lower end, and connects at its upper end with the support for the front edge of the bearing, a spring that rests upon the eccentric bearing and has its rear end secured to the forks by means of the vertical support, a pulley attached to the outer end of the spring, and a belt which passes around the front wheel of the bicycle, and pulley, substantially as shown.

7. In a bicycle-frame, the standards E secured thereto at their lower ends, the braces I secured to the frame at their rear ends, and the rod G which connects the front ends of the braces and the upper ends of the standards, combined with an eccentrically-pivoted bearing placed on the rod; a spring resting upon the bearing, the pulley secured to the outer end of the spring, a support which rises from the braces and serves to connect the inner end of the spring to the braces, substantially as described.

8. The bicycle-frame, the standards E, the braces I, and clasps for securing the standards and the braces to the frame, and the rod G for rigidly connecting the ends of the standards and the braces, combined with an eccentrically-pivoted bearing.

trically-pivoted bearing, means for regulating the position of the bearing, a spring resting upon the bearing, means for connecting the spring to the bicycle-frame, a roller secured to the outer end of the spring, and a belt which passes around the roller and the wheel of the bicycle, substantially as described.

9. In a bicycle, the standards E, the crossed braces I, suitable clasps for connecting the standards and braces to the bicycle-frame, the rod G for connecting the ends of the standards and braces, and the eccentrically-pivoted bearing, having a rounded top and end flanges,

combined with a flat spring that has its rear end secured to the braces, a roller secured to its outer end, a belt which passes around the roller, the rod c' which passes through the spring and secures it to the braces, and the rod b' connected to the bearing and provided with means at its upper end for holding the bearing in any desired position, substantially as shown.

WILLIAM FREMONT GLIDDEN.
